GEOMETRICAL INSTRUMENT

John K. Barns, Bement, Ill.

Application March 4, 1939, Serial No. 259,913

2 Claims. (Cl. 33—114)

This invention relates to new and useful improvements in geometrical instruments and more particularly to a knock-down square.

The principal object of the present invention is to provide a geometrical instrument in the form of a square of substantially large size which can be usually knocked down to shorten the same to facilitate its placement in a tool chest.

Other objects and advantages of the invention will become apparent to the reader of the following specification.

In the drawings:

Figure 1 represents a fragmentary plan view of the square assembled.

Figure 2 is a plan view of the angle section.

Figure 3 is a fragmentary plan view of the leg section.

Figure 4 is a section on line 4—4 of Figure 1.

Figure 5 is a section on line 5—5 of Figure 1.

Figure 6 is a section on line 6—6 of Figure 2.

Figure 7 is an elevational view of the rotary detent.

Figure 8 is a sectional view on line 8—8 of Figure 3.

Figure 9 is a sectional view on line 9—9 of Figure 3.

Referring to the drawings wherein like numerals designate like parts, it can be seen that the square consists of the sections A and B. The section A is of right-angular construction and consists of the leg 5 and arm portion 6.

The arm 6 has graduations 6a and 6b along its inner and outer edges, while the leg 5 has graduations 5a along its outer edge and numerals 35 5b along its inner edge which are matchable with the numerals 7a on the leg extension 7, the latter having graduations 7b which form a continuation of the graduations 5a and graduations 7c along its inner edge portion. The numerals 40 7a of the leg extension 7 form a continuation of the scale 7d in conjunction with the numerals 5b of the leg 5.

The end portion of the leg extension 7 adjacent the section A is reduced in width. As a matter of fact it is reduced to substantially half of its width and its reduced width matches the width of the leg 5, thus defining the shoulder 8 in the leg extension 7 against which the end 9 of the leg 5 can abut.

50 A reduced lug 10 projects from the shoulder 8 and has its outer end beveled as at 11 and further formed with a transverse channel 12.

The adjacent end of the leg 5 is reduced in thickness to form the thin cross member 13 55 inwardly of which is the opening 14 having the beveled wall 15 at its inner end.

Obviously the lug 10 can be slipped upwardly through the opening 14 so that the cross member 13 will seat in the channel 12 of the extension 7 while the beveled end 11 of the lug 10 will

rest against the beveled wall 15, so that seating action as shown in Figure 4 will take place.

A rotary detent 16 is provided in the free end of the reduced portion of the leg extension 7. This is in the form of a rivet having a winged head 17 and a kerf 18 for the reception of a screw driver or other tool. The head 17 can be disposed through the double key hole slot 19 of the arm 6 adjacent the leg 5 to the end that the free end of the reduced portion of the leg extension 7 will seat the leg 5 to the end which the detent 16 can be rotated so that the head 17 with its wing members 21—21 will interlap the arm 6 and prevent displacement of the leg extension therefrom.

While the foregoing specification set forth the invention in specific terms, it is to be understood that numerous changes in the shape, size and materials may be resorted to without departing from the spirit and scope of the invention as claimed hereinafter.

Having described the invention what is claimed as new is:

1. A geometrical instrument comprising a square, a detachable leg extension, said leg extension being provided with a reduced end portion adapted to extend parallel to and match one leg portion of the square, the other leg portion of the square having a recess in its end portion adjacent the matched leg portion for receiving the free end of the reduced portion of the leg extension, securing means between the free end portion of the reduced portion of the leg extension and the square at the recess, and securing means between the free end portion of the matched leg portion of the square and the leg extension.

2. A geometrical instrument comprising a square, a detachable leg extension, said leg extension being provided with a reduced end portion adapted to extend parallel to and match one leg portion of the square, the other leg portion of the square having a recess in its end portion adjacent the matched leg portion for receiving the free end of the reduced end portion of the leg extension, securing means between the free end portion of the reduced portion of the leg extension and the square at the recess, and securing means between the free end portion of the matched leg portion of the square and the leg extension, the reduced portion of the leg extension defining a shoulder between itself and the extension proper, the free end of the matched leg of the square being formed with an opening, and a lug on the shoulder for engaging into and latching the matched leg portion of the square with the leg extension when the free end of the reduced portion of the leg extension is secured to the square at the recess.

JOHN K. BARNES. 60
